UNITED STATES PATENT OFFICE.

WILLIAM J. MAGINNIS, OF PHILADELPHIA, PENNSYLVANIA, ASSIGNOR TO ROYAL ELECTROTYPE COMPANY, OF PHILADELPHIA, PENNSYLVANIA, A CORPORATION OF PENNSYLVANIA.

PLATE AND PREPARATION OF PLATE FOR ELECTROTYPEING.

Application filed November 7, 1924. Serial No. 748,434.

My invention relates to preparing pattern plates for electrotypes that, preparatory for use in printing, are to be used with the McKee overlay process. In this process the portions of the plate which are intended to print shadows are altered in position with respect to the remaining surface of the plate so as relatively to project from the face of the printing plate. This is accomplished by "overlays" of sheets of papers on the front of the high-light parts of the plate, preferably with underlays upon the back of the plate immediately back of the shadows. The plate is heated and pressed resulting in a distortion of the plane, bringing the shadows forward or forcing the high-lights back, whichever view may be taken of it, usually doing both and yielding a plate which will print with less pressure upon the paper than would otherwise be the case.

When electrotypes are intended for use with the "McKee overlay" process blank or non-printing portions of the plate must initially be original half tone height and these portions after the plate has been used in the McKee process must be routed down to below the printing surface before the plate can be used for printing. The height varies with printers; two heights used, among others, being .063 and .048.

The purpose of my invention is to provide a simpler, more rapid, and generally better way of preparing these patterns.

A further purpose is to provide standard divided moulds for pattern plates of standard size, separating generally parallel to the printing surface, clamping the original cuts or half tones and any electrotypes of printed matter, or other cuts intended to be used to position between the divided portions of the mould and then casting the "bearer" or non-printing border of the pattern and all intermediate non-printing portions about these cuts and electrotypes.

A further purpose is to increase the strength of the pattern and to reduce the requisite skill and time of manufacture.

A further purpose is to provide easy means for accurately positioning the original cuts and electrotypes of printed matter in the pattern by having lines of reference showing upon the bottom of the mould.

A further purpose is to avoid the necessity of engraving trimming lines and register marks on the surfaces of the bearers (blank border about the cuts and electrotypes, routed down before the plate can be used for printing) by suitably marking the cover of the mould.

A further purpose is to fill out low regions of the cuts and electrotypes enclosed within the pattern during the casting operation, connecting these low regions within the cuts and electrotypes to the border portion of the mould through registering holes and grooves at the bottom or low in the mould. For example, in the low region of a cut, a hole can be made through the cut to the bottom of the mould, and a groove can be extended from it to the border region of the mould, the groove being either in the bottom of the mould or in the bottom of the cut or electrotype.

Further purposes will appear in the specification and in the claims.

My invention relates both to the process involved and to the plate produced.

Ordinary type will not withstand the pressure of lead moulding to which the pattern is subjected when making the negative for the electrotype, so that heavy shell wax process electrotypes of printed matter for the pattern must be made from the type form. The electrotypes are backed and then shaved to the same thickness as the original cuts with which they are to be used, this thickness being normally .063 inches. Non-printing portions of both cut and electrotype to within $\frac{1}{8}$ inch of the printing surface are everywhere filled out to original half tone height.

A simple electroplate will contain head-line, folio, and illustration and a piece of type matter and prior to my invention when the plate is to be used in the McKee process before use in printing, the pattern plate from which the electrotype negative is to be lead moulded has been prepared as follows:

An electrotype-metal sheet several inches larger than the printing surface desired, is shaved to the thickness of the original illustration half tone or other cut (normally .063 inches). The zinc cut, line cut or half tone plate and the electrotypes of the head-

line, folio, and type matter are properly positioned upon the sheet and the positions of the plate and each electrotype are marked by scribing. The sheet is then cut out along the scribed lines and the cut and electrotypes are fitted into the openings and are soldered to the plate by means of soldering iron, flux and solder, the edges of the openings being routed to form grooves too narrow to interfere with the make-ready. All of the soldered joints are carefully leveled that no depression or raised portion may appear on the pattern and later on in the electroplate. Trimming lines and register marks, for use in the overlay process, are then engraved on the surface of the bearers, to appear ultimately on the electroplate.

In this preliminary process, differing from plain electrotyping in the presentation of a substantially complete full height surface, a great deal of time, attention and skill are required; and often with that the personal equation enters considerably, in that the accuracy of the cutting of the openings, the uniformity or lack of uniformity of the soldering temperature, the proper cleansing of the surfaces for soldering, all affect the strength as well as the accuracy of the resultant plate.

The same method is used whether there be one or more than one original illustration cut, and one or more than one electrotype block of type, for insertion, the work being correspondingly greater with an increase in the number of inserts.

My invention avoids the need for shaving the blank bearer sheet to the thickness of the original cut, the need for scribing and mortising holes in the sheet, of soldering the inserts to place with careful leveling of the soldered joints, avoids the need for engraving trimming lines and register marks upon the surface of the bearers, avoids any material increase in the work with an increase in the number of inserts, and moreover materially lessens the requisite quantity of bearer metal that must be kept ready to meet a given daily output of patterns.

In the drawings similar numerals refer to like parts in all figures.

Figure 1 is a top plan view of the lower portion of the divided mould.

Figures 2 and 3 are sections of Figure 1 taken respectively upon the lines 2—2 and 3—3.

Figure 4 is a bottom plan view of the cover.

Figure 5 is a plan view showing halftone and electrotype inserts positioned within the lower portion of the mould.

Figures 6 and 7 are sections of Figure 5 taken upon the lines 6—6 and 7—7.

Figure 8 is a plan view with the cover broken away to show the cast pattern within the mould.

Figure 9 is a section of Figure 8 taken upon the line 9—9.

Figures 10 and 11 are top plan views of the pattern as removed from the mold, that in Figure 11 being routed about the cuts and electrotypes.

Figures 12 and 13 are sections of Figure 11 taken upon the lines 12—12 and 13—13.

Figure 14 is a top plan view to reduced scale illustrating the procedure used to fill 75 in a hollow within the cut.

Figure 15 is a section of Figure 14 upon line 15—15 thereof.

Similar numerals indicate like parts in the drawings.

Describing in illustration and not in limitation and referring to the drawings:—

By my process the cuts which are intended to be incorporated in the plate are placed in a metal mold of original half tone height, 85 having bottom 16 and cover 17 intended for die casting. The printing surfaces 18, 19, 20, 21 and 22 are coated with whiting to prevent the metal to be cast from flowing into the spaces within their surfaces which 90 are not of full height because non-printing surfaces and which are not of sufficient area to justify forcing them to the level of the printing surface.

The placing of the cuts is facilitated by a scale in the form of squares or other markings shown at 23 in the bottom of the die casting mold and markings such as trimming lines. Register marks intended to be placed uniformly upon these preliminary 100 plates or upon the electrotypes made from them may be cut into or marked upon the inner face of the cover as at 24, 25.

The plates 18—22 of any desired number and including all of the varieties of cuts 105 and plates which could be incorporated by the prior method and properly cleaned to provide good contact surfaces are coated at their edges with soldering flux and are placed in their proper positions. The cover is then clamped on to keep the mold closed about the edges and at the same time to clamp the plates in the position in which they have been set. This may be effected preferably by making the cover plate stiff enough to hold the parts in the position set and at the same time to bring the cover effectively against the edges of the bottom part of the mold about the opening. In determining the height of the edges of the bottom part relative to height of the plate-high cuts the coating of whiting over the printing surfaces of the cuts must be considered, to clamp the cuts finally and seal.

The same effect could be produced by the 125 use of a more flexible cover with clamps about the edges and with clamps engaging the cover and bottom on opposite sides of the cuts at the points of insertion.

I have shown conventional forms of clamp 130

26 embracing the cover along approximately the middle of the sides of the mold and cover.

After the mold has been clamped shut 6 with the plates in position it and the plates are heated to a temperature high enough to prevent chilling of the metal poured so as to insure thorough distribution of the metal throughout the spaces intended for it.

10 The temperature to which the mold is heated preferably approximates the pouring temperature of the metal poured. This metal may be the same as the metal from which the border was made in the process as 15 formerly practised and is preferably of the same general character as stereotype metal.

The hot metal is then poured into the mold and forms a complete union with the cuts or plates just as in the case of soldering, except that it is much more complete 20 and uniform, corresponding with perfect soldering at the right temperature done coincidentally about the entire surface.

Though this is not essential, I prefer to 25 cast the metal 27 solidly up against the edge of the printing surface of the plates as seen in Figure 10 and afterward rout out the narrow groove 28 adjoining the plate which is desired for the carrying out of the McKee 30 process, rather than to attempt to fill in the spaces represented by this groove about the plate with whiting or other material before the casting so as to avoid this cutting operation. For this reason I have illustrated 35 the finished plate as having the groove about each cut or plate and cut the groove by any suitable tool as by a routing cutter after the completion of the casting operation. It will also contain the reverse 24', 25' of the 40 markings 24, 25 upon the cover 17.

Where the outline of any cut completely surrounds the depressed non-printing surface—as in Figures 14 and 15 and it is desired to cast metal within this enclosed 45 printing surface to fill up the non-printing space, I accomplish this in my process by cutting openings 29 through the back of the plate at several points so as to permit flow of molten metal freely through these several 50 grooves into the non-printing depression of the plate.

Passages for outlet of air from the plate may be provided at 30 and the openings formed at 29 as above should be selected with 55 a view to permitting the enclosed air to escape from the interior of the surrounded non-printing space. The opening within the plate must be deep enough below the printing surface to avoid danger of disturbing 60 the printing surface.

In operation, the plates to be incorporated are rested on the flat bottom of the body portion of the mould (as distinguished from the cover) in the relation to each other and 65 to the border which they are to bear in the

completed plate. Soldering flux is applied to the edges preferably before they are placed. The cover of the mould is then put in place and the mould bottom and cover sections are clamped together to close the mould and 70 at the same time to hold the plates in the position in which they have been set. The mould is then turned up on edge and the molten metal is poured into it, the mould being heated to prevent chilling of the 75 molten metal. The molten metal effectually unites with the edges of the plates to form a thorough mechanical (soldered) union.

Whatever markings have been placed upon the inside of the mould face of the cover 80 will appear in reverse upon the completed casting.

It will be evident that the plate insert or inserts within the mould may be regarded singly or together as forming a plate make 85 up of full height.

In view of my disclosure, various modifications and changes in my invention to suit individual whim or the needs of variant service will occur to those skilled in the art 90 and it is my purpose to include herein all such as lie within the reasonable spirit and scope of my claims.

Having thus described my invention, what I claim as new and desire to secure by Letters Patent is:—

1. A mould having a body section carrying indices balanced on opposite sides of the center to assist in accurately setting plates therein, having a top adapted to mould 100 bearers the height of original half tone plates about the plates and open along an edge for the receipt of molten metal.

2. A casting mould separable along lines substantially parallel with the printing surface and spaced between parallel cover and body casting faces by the height of an original half tone plate, to clamp printing plates between them and having space between the faces outside of the position of 110 the printing plates within which bearers of the same height are cast about the plates.

3. A mould body having raised sides and open along one edge for receipt of molten metal, in combination with a cover sealing 115 therewith about the sides, spaced internally from the bottom between the sides to the height of original half tone plates, plates secured within the mould in the positions which they are to occupy in a composite 120 printing plate and soldering flux upon the edges of the plates.

4. A mould body having raised sides and open along one edge for receipt of molten metal in combination with a cover sealing 125 therewith about the sides, spaced internally from the bottom between the sides to the height of original half tone plates and adapted to receive plates, solder-fluxing for the edges of the plates, the plates be- 130

ing located within the mould in the positions which they are to occupy in a composite printing plate and the interior of enclosing printing surface upon a plate being connected with the space for molten metal in the mould by a passage extending beneath the printing surface.

5. The method of casting material of full plate height about printing plates and incorporating them in a composite plate which consists in placing the plates in their pre-

determined relation upon a mould wall, fluxing the edges of the plates, protecting small non-printing surfaces by filling them in, concurrently protecting the actual printing surfaces from the molten metal and clamping the plates in position by a second mould wall, spaced from the first and pouring molten metal between the two walls and about the plates while closing the edges of the space about the plates against leakage.

WILLIAM J. MAGINNIS.
